Ward Crosby and Stark

UNITED STATES PATENT OFFICE.

WALTER F. HEROLD, OF NEWARK, NEW JERSEY, ASSIGNOR TO THE BASSICK COMPANY, OF BRIDGEPORT, CONNECTICUT, A CORPORATION OF CONNECTICUT.

CASTER.

Application filed September 21, 1922. Serial No. 589,502.

To all whom it may concern:

Be it known that I, WALTER F. HEROLD, a citizen of the United States, and resident of Newark, in the county of Essex and State 5 of New Jersey, have invented certain new and useful Improvements in Casters, of which the following is a specification.

The invention relates to improvements in casters, and particularly to casters of the 10 type known as gripneck casters, in which the pintle is removably inserted within a socket having an inwardly extending spring portion through which a head or enlargement of the pintle is forced when the pintle 15 is mounted in position, the spring coacting with the pintle enlargement or head to prevent the caster from falling out of place when in use. In such casters the socket, except for its spring portion, commonly fits 20 closely within a vertical opening in a wooden furniture leg or the like.

In the usual prior constructions of this type the pintle is of uniform diameter, less than the inside diameter of the socket, 25 throughout its length, or throughout the intermediate portion of its length, within the socket, up to the enlarged upper end or head, below which the spring portion of the socket engages. Such pintles are commonly formed by upsetting a length of 30 wire rod to form a head on one end and by providing a shoulder adjacent the other end adapted to be secured to the top of the caster 35 horn. The head of the pintle must be adapted to pass through the solid portion of the socket when the caster is to be withdrawn, and the body of the pintle below the head is, of course, of an even smaller diameter, so that it will fit quite loosely in the 40 socket.

With such an arrangement lateral pressure exerted on the caster wheel or bearing member tends to cause a tilting of the pintle which is resisted by the pressure of the 45 spring portion of the socket against the upper portion of the pintle. In the use of the caster the spring portion of the socket is thus repeatedly bent laterally, whereby its spring action is weakened, and in many 50 cases the spring is permanently distorted, so that it will not prevent the head of the

pintle from dropping therethrough when the furniture is lifted.

An object of the present invention is to provide a construction in which such defective operation is prevented. In my improved caster the lower portion of the pintle is adapted to fit slidably within the solid portion of the socket, with a bearing immediately below the socket spring portion. 55 The pintle is given a reduced diameter (and is preferably tapered) from a point adjacent to the lower end of the spring portion of the socket to the lower side of the pintle head, which latter is adapted to slide 60 through the solid portion of the socket when the pintle is inserted in position. The pintle and the bottom of the socket are preferably formed to provide a thrust and journal bearing at this point, by giving the pintle a 65 sufficiently steep outward taper or curve adjacent its lower end, so that sidewise movement of the bottom of the pintle will be prevented, regardless of slight variations in clearance between the pintle stem and solid 70 wall of the socket, which must be expected in practical manufacturing operations.

With such a construction, lateral pressure exerted on the caster wheel tends to tilt the pintle, but such action is resisted by the 75 lateral pressure of the pintle against the solid part of the socket immediately below the spring portion of the socket, and lateral pressure of the pintle against the spring portion of the socket in such a case cannot 80 occur, to any marked extent. Accordingly the distortion of the spring portion of the socket, referred to above, is prevented. The arrangement described also permits the use 85 of pintles of thicker stock, adapted for 90 heavier duty, than is possible for use with sockets of the same size, when the pintle is of uniform diameter for its length below the head, within the socket.

The invention includes the provision of 95 improved casters and pintles therefor, of the character referred to, as articles of manufacture. The invention comprises various arrangements, combinations and details of construction, all as will be more fully described 100 hereinafter and particularly pointed out in the accompanying claims.

In order that the invention may be more fully understood, attention is hereby directed to the accompanying drawings, forming part of this application, illustrating one embodiment of the improved construction.

In the drawings Fig. 1 is a side elevation of the preferred form of pintle before the same has been secured to the caster horn, and

10 Fig. 2 is a view partly in side elevation showing the completed caster mounted in position within a wooden furniture leg.

Referring to the drawings, the pintle may be formed in any suitable way from steel or 15 other suitable material. The complete pintle, of preferred form, is shown in Fig. 2, in which it is seen to have a lower body portion, 2, of uniform diameter; a tapering portion, 3, above the same, a head, 4, at the 20 upper end of tapered portion 3, and a peripheral shoulder 5 at the lower end of lower body portion 2.

The pintle may be secured to the top cross portion 18 of the caster horn in usual fashion, as by inserting portion 17 of the pintle 25 through an opening in member 18 and upsetting the lower end of the portion 17 to form a head or shoulder 19 thereon, below portion 18 of the horn.

30 In the pintle a fillet or tapered surface 20 is preferably formed in any suitable manner at the junction of portion 2 of the pintle with shoulder 5, this fillet or tapered surface forming at least a part of the upper surface 35 of the shoulder, as is indicated particularly in Fig. 1.

The complete pintle, secured to the caster horn, is shown mounted in position in Fig. 2. The socket 21 is secured to the supporting 40 disc 22 in usual manner, the socket then being forced into position in the opening 23 of the wooden furniture leg 24, disc 22 being shown as provided with a serrated edge 25 which is forced into the lower edge of the wood. The upper part of the socket is 45 shown as cut longitudinally to form spring fingers, 26, arranged to exert pressure inwardly, in well-known manner.

The solid portion of the socket, below the 50 spring fingers 26, fits closely within opening 23. When the pintle is pushed into position, head 4 will move through the socket, pushing spring fingers 26 aside, and will take the 55 position shown in Fig. 2, above the spring fingers. The spring fingers preferably will be out of contact with the surface of the tapered portion 3 of the pintle, so as not to interfere with the rotation of the pintle about its axis, in use. The upper ends of 60 the spring fingers, however, are below the head 4, and the pintle may only be withdrawn by pulling on the same with enough force to draw head 4 through spring fingers 26.

65 The portion 2 of the pintle will have a

sliding fit in the solid portion of the socket, portion 2 extending upwardly to approximately the base of the spring portion 26 of the socket. Collar or shoulder 5 of the pintle will bear against the turned under lower 70 end portion 27 of the socket. Fillet 20 on the pintle will fit snugly against the curved inner surface of end portion 27 of the socket, and will form with it a combined thrust and journal bearing.

75 When caster wheel 28 encounters resistance, in moving the furniture over an uneven surface, for example, the tilting effect produced on the pintle will cause lateral pressure of the upper part of portion 2 of 80 the pintle against the solid wall of the socket, which is backed by the solid wood of the furniture leg, 24, below the spring portion of the socket. Portion 3 of the pintle being of reduced diameter relative to 85 portion 2 such tilting effect cannot cause lateral pressure of the pintle against the spring 26, to any perceptible extent. The provision of fillet 20 on the pintle, seating 90 against the correspondingly curved surface at the bottom of the socket, also tends to insure a lack of looseness of fit of the lower portion of the pintle in the socket.

In manufacturing practice, it is impossible 95 to manufacture the pintles and sockets in

quantity exactly to size, a tolerance or variation of some thousandths of an inch, say ten thousandths of an inch for the pintle and also for the socket, having necessarily to be allowed for. Therefore, it 100

is not possible to have the upper journal bearing of the pintle, immediately below the socket spring, fit with absolute snugness in all cases, although what is commonly termed 105 a sliding fit is obtained. At the lower end of the pintle, however, no lateral movement of the pintle in the socket will be permitted, since the curved or tapered surface at the upper side of shoulder 5 will engage at all times, in the service of the 110 caster, with the curved lower edge of the socket, which will effect at least a line contact all the way around the periphery of the pintle. Accordingly any tilting effect 115

on the pintle may cause a very slight rocking of the pintle about the bearing of fillet 20 and the lower end of the socket as a pivot, such rocking being limited by the firm engagement of the upper part of portion 2 of the pintle with the wall of the 120 socket which is backed by the solid wood of the leg. Such a tilting can be for a very slight angle only, and will produce practically no strain on the socket spring, as stated. If, however, the lower end of the 125 portion 2 of the pintle were free to move laterally a few thousandths of an inch, as it would be except for the provision of the inclined surface 20, the lateral movement 130 of the upper end of the pintle would be

multiplied to, for example, three times that of the lower end, or of the upper end, of portion 2, assuming equal clearance at the top and bottom of portion 2 and a length of 5 portion 2 about equal to that of tapered portion 3 of the pintle. In this case the strain on the spring might well be severe.

The provision of the tapered or curved surface 20 on the pintle also aids in aligning 10 or keeping the pintle coaxial with the socket and the opening in the leg at all times, and makes the caster swivel more easily, because of the fact that swiveling requires more force with a tilted pintle 15 than with a properly aligned one. The construction also reduces the bending stresses on the pintle, as these are also increased when the pintle is tilted over at an angle.

It should be understood that the invention is not limited to the exact details 20 of construction which have been particularly pointed out. The scope of the invention will be indicated by the accompanying claims.

25 What I claim is:

1. In a gripneck caster, the combination of a socket having a spring top portion and a leg supporting plate at the bottom, and a pintle having a cylindrical portion 30 adapted to slidably fit in said socket up to the base of the spring portion thereof with a clearance held within narrow limits, the pintle having an enlargement below said socket the upper surface of which tapers 35 upwardly and inwardly to connect with the cylindrical surface, to form a thrust and journal bearing for the bottom end of said socket, arranged to engage the socket in at least line contact around its periphery 40 regardless of slight variations in the clearance of said cylindrical pintle portion, said pintle having a portion of reduced diameter above said cylindrical portion and a head at the top of said reduced portion, 45 above the upper end of the socket spring portion when the pintle is mounted in position.

2. In a caster, the combination of a cylindrical socket having an inwardly extending 50 spring portion forming its upper end, and a pintle having a cylindrical portion of uniform diameter adapted to slidably fit in said socket from the lower end of the same to the base of the spring portion of the same, and having a portion of reduced diameter 55 extending from said first portion to a point above the upper end of said socket spring portion, and having a head above the upper end of said spring portion, when the pintle 60 is mounted in position, said pintle having a peripheral shoulder at its lower end and said socket having a leg supporting plate secured to the lower end thereof, the lower end of the socket bearing upon said shoulder, and 65 the pintle, at the junction of said cylindrical

portion and shoulder, having a snug rotative fit in the socket.

3. In a caster, the combination of a socket having an inwardly extending spring portion at its upper end and an outwardly and downwardly curved edge at its lower end, and a pintle having a shoulder adjacent its lower end adapted to bear against said socket lower end with a fillet adapted to fit against said socket curved edge, said pintle 70 having a portion extending upwardly from said fillet adapted to slidably fit in said socket up to the base of the spring portion of the same, with a bearing surface engaging the socket wall immediately below the base 75 of the spring portion, and having a portion of reduced diameter extending from said first portion to a point above the upper end of said socket spring portion, and having a head above the upper end of said spring portion, when the pintle is mounted in position.

4. In a caster, the combination of a socket having an inwardly extending spring portion forming its upper end, and an outwardly and downwardly curved edge at its lower end, and a pintle having a shoulder adjacent its lower end, portions slidably fitting and forming bearings within said socket adjacent the lower end thereof and just below the base of said spring portion, respectively, a portion of reduced diameter 90 extending upwardly from said last named portion to a point above the upper end of said spring portion, when the pintle is mounted in position, the pintle having an inclined peripheral surface at the junction of said first named bearing portion and shoulder, adapted to form a thrust and journal bearing for the curved lower edge of said socket.

5. A caster pintle having a peripheral shoulder adjacent its lower end, a cylindrical portion of uniform diameter extending upwardly from said shoulder for a substantial part of the length of the pintle towards 100 the other end, and a downwardly inclined fillet connecting said shoulder and portion of uniform diameter and constituting part of the upper surface of said shoulder, said fillet being adapted to bear against a curved seat at the lower end of a socket and said portion of uniform diameter being adapted to slidably fit in such a socket, said pintle 110 having a portion of reduced diameter of substantial length, following said first 115 named portion, and a head, of diameter no greater than that of said first named portion, immediately beyond said portion of reduced diameter.

6. In a gripneck caster, the combination of 125 a cylindrical socket adapted to be driven into an opening in an article to be supported, having an inwardly extending spring portion, and a supporting plate at the bottom, and a pintle having a pair of portions adapt- 130

ed to slidably fit in said socket and form journal bearings at separated points therein, at which the socket wall is backed solidly by the material of the article supported, the upper of said portions fitting in said socket with a clearance held within close limits, and the lower of said portions being formed to effect with the lower end of said socket

a combined thrust and journal bearing, said pintle also having an enlargement adapted to pass through said socket spring portion and retain the pintle therein.

In testimony whereof I have signed my name to this specification, at Newark, New Jersey, on this 6th day of Sept. 1922.

WALTER F. HEROLD.
